US0D1016939S

(12) **United States Design Patent** (10) **Patent No.:** **US D1,016,939 S**
Liu (45) **Date of Patent:** **** Mar. 5, 2024**

(54) **DEADLIFT BARBELL DROP LOAD UNLOAD SYSTEM**

(71) Applicant: **QIDUO E-COMMERCE (ZHEJIANG) CO., LTD.**, Ningbo (CN)

(72) Inventor: **Guangchao Liu**, Hengyang (CN)

(73) Assignee: **QIDUO E-COMMERCE (ZHEJIANG) CO., LTD.**, Ningbo (CN)

(**) Term: **15 Years**

(21) Appl. No.: **29/839,232**

(22) Filed: **May 19, 2022**

(51) LOC (14) Cl. **21-02**

(52) U.S. Cl.

USPC **D21/694**; D21/662; D21/671; D21/681; D21/686

(57) **CLAIM**

The ornamental design for a deadlift barbell drop load unload system, as shown and described.

DESCRIPTION

FIG. 1 is a perspective view of a deadlift barbell drop load unload system, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines in FIG. 7 show portions of the deadlift barbell drop load unload system that form no part of the claimed design.

1 Claim, 7 Drawing Sheets
